Application October 11, 1951, Serial No. 250,867

3 Claims. (Cl. 315—22)

1

This invention relates to improved cathode ray tube apparatus for reproducing images in color. Color kinescopes have been constructed employing directional color screens that emit light of one primary color or another depending on the direction of approach of the beam of electrons toward the screen. In one particular type of screen, three different phosphors are mounted at different radial angles with respect to a given center. Generally the phosphors are at radial angles that are 120° apart and thus each phosphor may be considered as being centered at one apex of an equilateral triangle. Each set of three phosphors forms a group. The groups are arranged in a row, alternate groups being mounted with the perpendicular bisector of one particular side of the equilateral triangle pointing in opposite directions that are perpendicular to the row. Thus one side of alternate triangles is parallel to the upper edge of a row and the corresponding side of intermediate triangles is parallel to the bottom side of a row. The phosphors may be spots on a plane surface, they may be coated onto three sides of a solid such as a pyramid, or, they may be coated on the insides of a hollow hexahedron, etc. The important factor is that the different color responsive phosphors must be arranged so that they can be scanned in one order by a beam tracing a closed nonintersecting path in one direction and in a reverse order when the beam traces a different closed path but in the same direction. A target formed in this manner will be referred to as a directional target.

The directional target is activated by a single beam that is rotated about its normal path so as to approach the screen from cyclically changing directions. The different color emissive phosphors are activated in a given order as the beam rotates in a given direction with respect to the geometric center of one set of the phosphor groups.

As pointed out in the U. S. patent application bearing Serial No. 220,622, filed on April 12, 1951, in the name of Sziklai, Schroeder and Bedford, improved results can be obtained if the transmitted signal represents the primary colors in one sequence during one interval of time and a reverse sequence during another interval.

It is the principal object of this invention to provide a new and improved way of reversing the sequence in which the different primary colors are emitted by color kinescopes of the type described above.

Briefly this objective may be attained by shift-

2

ing the centering of the beam or beams of electrons before they are focussed so that a different group of phosphors is scanned. In addition, for reasons that will be treated in detail below, the phase of the rotation of the beam about its normal path must be altered when the centering is changed.

The manner in which this objective may be reached will be better understood from the detailed description of the drawings in which:

Figures 1 and 1A show the details of a single beam color kinescope that may be employed in the combination of the present invention.

Figure 2 is a view of the phosphor dot screen as it is seen through the mask of the color kinescope of Figure 1.

Figure 3 is a view of certain of the apparatus in Figure 1 useful in explaining the operation of the present invention.

Figure 4 illustrates a circuit that may be employed to change the centering of the beam on successive fields.

Figure 5 is an enlarged view of the phosphor spots employed in one type of directional screen and

Figure 6 illustrates a type of coincidence circuit that may be employed.

Referring to the drawings, Figure 1 shows one form of single beam color kinescope that may be used in the present invention. The tube consists of an evacuated envelope 10, having both a conical portion 12 and a tubular neck portion 14 coaxially joined together as shown. The conical portion 12 of the envelope is closed by a face plate 16 and closely spaced from it is a fluorescent target and screen structure 18 to be described below. Mounted coaxially within the tubular envelope 14 is an electron gun structure for projecting a beam of electrons 20 toward the screen structure 18. The electron gun is of conventional design and consists of a cathode cylinder 22.

A control grid cylinder 24 coaxially surrounds the electron emitting end of the cathode 22 and has an apertured plate structure closing one end thereof and closely spaced from the cathode. A shield electrode or grid 26 constitutes a short thimble-like electrode having an aperture in the bottom thereof for the passage of electrons therethrough. Spaced along the tubular neck portion 14 and coaxial with the other electron gun parts is a tubular first anode electrode 28, having an enlarged portion at the end facing the fluorescent screen 18. A second anode electrode is formed by a conductive coating 30 on the inner

surface of the tubular envelope portion 14 and extends into the conical envelope portion 12 to a point adjacent the fluorescent screen 18. The several electrodes described, which constitute the electron gun structure of the tube are connected to a source of direct current potential which may be a voltage divider 32 connected between the positive and negative points of a direct current potential source.

The electrostatic fields produced respectively between electrodes 26 and 28, and 28 and 30, are of a converging nature and cause the electrons to form into a beam having a minimum cross section or cross-over point 56 between the tubular electrode 28 and the screen 18. The electron beam, after passing through this cross-over point 56, tends to diverge before striking the screen 18. The diverged beam is bent away from the central axis of the tube by a rotating radial magnetic field. As is well known in the art, such a field can be generated by applying current of one phase to a first pair of coils that are diametrically mounted about the neck of the tube, and applying current of a different phase to a second pair of coils that are mounted with their axis at 90° to the first pair. For simplicity, the coils are shown as one yoke 61. The focusing coil 34 serves to converge the electrons within the beam and also to direct the beam to the same point in the region of the target 18. In the embodiment shown, this point is the same point on a mask 44 that the beam would have struck if the coils were not used. Thus the beam substantially generates a cone of revolution having an apex at the mask 44.

The electron beam 20 and hence the apex of the cone of revolution may be caused to scan over the surface of the mask 44 in any desired pattern or raster. However, in tubes of this type, the conventional scanning consists of parallel lines from top to the bottom of the screen 18. The scanning of the beam is produced by scanning fields established by two pairs of scanning coils included in the yoke 40. Each pair of coils may be connected to well known circuits producing saw-tooth currents for providing both line and frame scanning of the beam.

In the screen structure 18 the masking electrode 44 is positioned in front of a transparent phosphor supporting sheet 46. The masking electrode 44 is formed from thin metallic foil which is opaque to the electrons of the beam 20. A plurality of apertures 48 are formed through the metal foil of the masking electrode 44. Supported on the surface of the transparent plate 46 are areas 50 of phosphor coating which are positioned in the path of the beam 20 passing through apertures 48.

In the enlarged section of the screen 18 shown in Figure 1A it can be seen that if the electron beam approaches the target from any one of the directions indicated as X, Y or Z, the electrons of the beam will pass through the apertures of the masking electrode 44 and strike those phosphor spots which are in line with the beam path, coincident with these directions. When the beam approaches the target along a path "X" it strikes only those phosphor coated spots indicated by "R," which luminesce with a red light. In a similar manner, when the beam approaches the target along path "Y," it strikes only those areas indicated by the letters "G" which luminesce with a green light. If the tube is a three color tube, the electrons of the beam approach-

ing the target along a path "Z" will strike those phosphor areas indicated by the letter "B," which luminesce with a blue light.

Thus, the combined effects of the rotating field of coils and that of the focusing coil 34 result in beam 20 being first displaced from its normal path and then redirected along a new path to strike the surface of target 18 from sequentially different directions so as to strike the phosphor spots in sequence.

The cross sectional area of the beam at the mask 44 may be large enough to cover a plurality of the apertures 48. Electrons pass through each of the apertures covered by the beam to form 15 sectional beams having a direction depending on the rotational angle of the main beam about its normal path. As the main beam rotates, the sectional beams also rotate and scan circular paths on the screen 18 having centers 70. In 20 Figure 2 certain groups of phosphor dots 70 are so arranged that their geometric centers coincide with the center of the circular path traced on the screen 18 by the sectional beams. Assuming for the moment that the beam 20 is not scanning a raster, but is rotating about its normal position in a clockwise direction, it can be seen from an examination of Figure 2 that the sectional beams 70 will scan around the red, blue, and green phosphor spots of the groups 70 in the order named. Now if the centers of the substantially circular paths traced by the sectional beams are shifted to the corresponding points 72, the beam scans red, green, and blue phosphor spots in the order named. This order of scanning the spots is just the reverse of the order in which they are scanned before the change in centering occurred.

This desired shift in the centering of loci or paths traced by the sectional beams on the screen 18 can be effected in accordance with this invention by shifting the centering of the beam 20 at any point between the cathode of the tube and the field of influence of the deflection yoke 40. A highly satisfactory point for changing the centering is as it passes through the beam rotation coils. Whether the means employed is electrostatic or electromagnetic the shift should be in a direction that is the opposite from the direction 70 to 72; that is from 72 to 70. The reason for this will become clear from the following discussion of the electron optics of the tube of Figure 1. The essential components of the electron optic system are illustrated in Figure 3. The electron gun shown in Figure 1 directs a beam of electrons along the principal axis of the tube to a point "0" that is centrally located with respect to the rotating magnetic field set up by the beam rotation coils. In normal operation, the beam 20 is bent away from the principal axis of the tube and rotated. The paths "b," "m," and "g" indicate different positions that the beam 20 may assume as the radial magnetic field established by the coils rotates. The loci of the beam in the plane of the focusing coil 34 is a circle with its center at a point 73. If the current in the focusing coils is properly adjusted, the origin "0" of the beam is imaged at the point i. This latter point is at the apertures 48 of the mask 44 and is effectively the focal or cross-over point. With no current flowing in the deflection coils 40, the beam would generate a cone of revolution having its apex at the point i. Now if the beam is deflected, the apex scans to a point i'. It should be noted that the focusing coils serve

to focus at the point i or i' as the case may be, both the electrons within the beam and the beam itself, regardless of its position in the loci.

In one embodiment of this invention, the beam is shifted from the point 0 to the point $0'$ as it passes through the beam rotation coils. Thus the loci of the beam in the plane of the focusing coil 34 is indicated by the dotted circle 75 having a center 76 . As is well known to those skilled in the art, this change in the angle of approach to the focusing or converging lens will cause the point $0'$ to be imaged at point i'' instead of point i . If the rows of phosphor spots of Figure 2 are horizontal and the lines 77 and 78 indicate the horizontal and vertical axes respectively of the tube, the direction i, i'' is the same as the direction $70, 72$ (see Figure 2). The shift in the centering of the beam can be effected by a coil 79 that produces a magnetic field of proper polarity transversely across the path of the beam 20 and perpendicular to the direction $0, 0'$. The shift in centering might also be effected by electrostatic plates that set up an electrostatic field along the line $0, 0'$.

Normal centering of the beam and hence the raster on the tube may be effected by controlling the amount of steady current flowing in the deflection coils 40 . Thus normal centering acts the same as a steady amount of deflection, and the center of deflection is still the same as illustrated by the deflected beam in Figure 3 that strikes the screen at i' . When the normal centering control is adjusted, the beam still lands at the same place with respect to the phosphor groups. If the change in centering is such as to displace the electron paths toward the focusing field, however, the electrons approach the screen from a different direction and land at a different place on the screen 18 with respect to the phosphor groups. The shifting of the centering could take place at other points than the axial position of the beam rotation coils but must take place before the focusing field is reached.

This shift in the beam in one direction, upward and to the right as shown in Figure 3, actually displaces the scanned raster and hence signals representing a certain point in the scene being reproduced are reproduced at two different positions as the beam is shifted to effect a reverse sequence of color reproduction. This misregistration is negligible if the groups of phosphors are small in comparison with the maximum amount of detail to be reproduced. If the groups are relatively large, the horizontal displacement can be corrected by changing the phase of the incoming video signals that are used to modulate the intensity of the beam or beams with respect to the scanning action of the beam.

Figure 4 illustrates the manner in which the centering of the beam of the tube shown in Figure 1 may be shifted on successive fields. The transmitted signal is detected on a standard receiver 90 and applied to the grid of the color tube and to the deflection circuit 92 in the normal manner. The signals are also applied to a color synchronizing circuit 94 such as described in RCA Bulletins on Color Television and UHF October 1949. A sampling oscillator 96 is controlled by the synchronizing circuit 94 and provides the energy that is to be applied to the beam rotation coils. The sampling frequency applied by the oscillator 96 is applied to the grid of an amplifier 98 via a delay line 100 and to the grid of an amplifier 102 directly. The plates of the ampli-

pliers are connected to a source of positive potential by an inductance 104 and also are coupled to a beam rotation coil 60 . Thus if the amplifier 98 is conducting, the sampling frequency is applied to the beam rotation coil 60 with a delay determined by the delay line 100 and if the amplifier 98 is cut off and amplifier 102 is conducting, the sampling frequency is applied directly to the beam rotation coil 60 without any delay. The reasons for this delay will be discussed more fully in connection with Figure 5.

In order to shift the beam as previously discussed, the present apparatus supplies current to the centering coil 79 during one field and a different amount of current to this coil during a succeeding field. In order to effect this result, the horizontal and vertical sweep signals supplied by the deflection circuit 92 are applied to a coincidence circuit 106 which is described in detail in connection with Figure 6. The coincidence circuit provides a pulse at the beginning of every other field. These pulses are applied to trigger a multivibrator 108 . The multivibrator 108 may be a free running type having a cycle equal to two fields or it may be a monostable multivibrator that is triggered to an unstable state by the coincidence pulse, reverting to its stable state at the end of a field. In either case, the multivibrator 108 will provide, as is well known to those skilled in the art, oppositely phased rectangular waves as illustrated by the wave forms 110 and 112 . These wave forms are applied to the grids of the amplifiers 98 and 102 respectively so that one is conducting while the other is non-conducting and vice versa. Thus during one field the sampling frequency supplied by the oscillator 96 is applied to the beam rotation coils 60 via the amplifier 98 and the delay line 100 , and in the next field it is applied directly to the beam rotation coil 60 .

One output of the multivibrator 108 is applied to an amplifier 114 , the plate of which is connected to $B+$ via the beam centering coil 79 . Hence when the amplifier 114 is rendered conductive by the positive portion of the wave form 112 a large amount of current flows through the centering coil 79 . When the amplifier 114 is cut off during a negative portion of the wave form 112 the amount of current flowing through the beam centering coil 79 may be substantially zero. The amount of current flowing through the beam centering coil 79 when the amplifier 114 is conductive may be adjusted by rheostat 116 that is connected in parallel with the beam centering coil 79 . When the amplifier 114 is non-conductive, the amount of current flowing through the beam centering coil 79 can be controlled by a rheostat 118 that is connected between the plate of the amplifier 114 and ground.

The overall operation of the apparatus in Figure 4 is as follows. During one field the amplifier 98 may be cut off and the sampling frequency from the oscillator 96 is applied directly to the beam rotation coils 60 . At the same time, the amplifier 114 is rendered conductive and current flows through the beam centering coil 79 so as to shift the beam from the points 70 on the phosphor screen of Figure 2 to the points 72 . During the next field, however, the amplifier 98 is rendered conductive and the amplifier 102 is cut off, with the result that the sampling frequency supplied by the oscillator 96 passes through the delay line 100 before being applied to the beam rotation coils 60 . At the same time the amplifier 114 is rendered non-conductive

and a small or lesser amount of current flows through the beam centering coil 79 so that the beam strikes the phosphor screen of Figure 2 at points 70.

The following discussion relates to the reasons for the use of the delay line 100 in the apparatus of Figure 4. Figure 5 shows an enlarged view of some of the phosphor spots. When the locus traced by the rotating beam is centered at the points 72, and assuming that the beam rotation is in a clockwise direction, the order of color reproduction is red, green, blue, red, etc. When the beam is shifted so that the center of its locus is at the points 70, the same direction of rotation will scan the red, blue, green, red spots in sequence. This sequence, as previously noted, is the reverse of the sequence when it follows a path centered at 72. Assume that the beam is centered at the point 72 and that the resultant magnetic field is such that the beam strikes a red phosphor spot 120. If the beam is now shifted by the action of the beam centering coil 79 so as to follow a circular path having 70 for a center, the beam strikes a point midway between the red phosphor spot 120 and a blue phosphor spot 122. However, at this time the signal transmitted represents red and not a combination of red and blue. Therefore, in order to insure that the beam lands on the red spot, the phase of the beam rotation must be retarded by 60°. The delay line 100 must therefore introduce a delay of one-sixth of a cycle of the sampling frequency supplied by the oscillator 96.

Figure 6 illustrates one form that the coincidence circuit 106 of Figure 5 may assume. A multi-grid tube 125 is biased to cut off by placing a positive potential on its cathode as shown. The horizontal "flyback" pulses are applied to a grid 127 by an ordinary RC coupling network. The vertical "flyback" pulses are differentiated by an RC coupling network 128 before being applied to a grid 129. When the two "feedback" pulses occur simultaneously, as is the case on every other field, the cut off bias on the cathode of the tube 125 is overcome and a pulse appears at its plate. It is this pulse that triggers the multivibrator 108.

In the embodiment of the invention discussed above, the beam would nominally strike the screen 18 at the points 70. The order of scanning the spots was reversed by shifting the beam so that it would normally strike the screen 18 at the points 72. Little or no current would then be passed through the beam shifting coil 79 when the path of the beam was to be centered at the points 70 and a predetermined amount of current would be in the coil 79 when the beam is to be shifted so as to trace paths centered at points 72. The beam might normally be centered at any point on a line between the points 72 and 70 in which case the current through the coil 79 would flow in one direction when the path of the beam on the screen 18 is to be at points 72 and in the opposite direction when the path of the beam is to be centered at points 70. If the beam would normally land at points on the screen 18 that are not along a line 72-70, then two sets of beam shifting coils providing intersecting fields would have to be used. Current through one of them would center the path traced by the beam at points 72 and current through the other would center the path traced by the beam on the screen 18 at points 70.

The beam could also be shifted downward so

as to trace the group of phosphor spots centered at the point 150 of Figure 2 so as to effect reversal of the sequence in which they are scanned by the rotating beam. In this case the delay line 100 would delay the output of the oscillator 96 of Figure 4 by one half cycle of the beam rotational frequency.

It is not necessary that the center of the path traced by the beam or the screen 18 be shifted to the nearest group of phosphors that provides reversal of the primary color reproduction. The shift can skip any number of groups as long as the groups traced after the shift are such that rotation about them in same direction produces a reversal in the sequence with which the phosphors of the different primary colors are scanned.

The apertures 48 in the mask 44 could also be oriented differently with respect to the phosphor groups without interfering with the present invention.

Having thus described the invention what is claimed is:

1. Cathode ray tube apparatus comprising in combination a directional target having different color phosphors mounted in groups along each line of the raster, an electron gun adapted to direct a beam of electrons toward said target along a given path, means for bending said electrons away from said path, the plane in which said bending occurs being rotated, means for focusing said beam in the region of said target, means for deflecting said beam so that it scans a raster at said target, means located between said gun and said focusing means for directing the electrons along a given path during a first interval and for directing said electrons along a different path during a second interval whereby said rotating beam scans the different color phosphors on said directional target in one sequence during the first 40 interval and in reverse sequence during the second interval.

2. Apparatus for reproducing images in color in response to signals that are derived by sampling at a rate greater than line frequency the primary colors of a scene in one order for a first interval of time and in a reverse order during a second interval of time comprising in combination a cathode ray tube, a directional color screen mounted in said tube, an electron gun adapted to direct a beam of electrons toward said screen along a given path, means for bending said beam away from said path, the plane of said bending being rotated, means for focusing said beam at a point in the region of said screen, means for laterally shifting said beam before it passes through said focusing means, means for causing said beam to scan a raster on said screen, means for controlling said beam shifting means so that the beam follows one path during said first interval and a different path during said second interval, and means for changing the phase of said rotating plane during said second interval.

3. Apparatus for reproducing images in color from color signals that are derived by sampling each of a plurality of primary colors from a scene in one sequence for a first interval of time and in reverse sequence for a second interval of time comprising in combination a target comprised of a phosphor dot screen, an apertured mask mounted in front of said screen, an electron gun adapted to project a beam of electrons toward said screen, means for establishing a rotating radial magnetic field that is perpendicular to said beam, a focusing coil adapted to converge said

electrons at the apertures in said mask, said focusing coil being mounted so as to act on said electrons after they have passed through said rotating magnetic field, a deflection yoke adapted to cause said focussed electrons to scan a raster at said target, means for establishing a transverse magnetic field that is at right angles to said beam, said latter means being mounted so as to shift said beam at a point before it enters the influence of said focusing field, and means for mak-

ing the magnitude of said transverse magnetic field different during only one of said intervals.
